(57) **CLAIM**

I claim the ornamental design for a portable information terminal having a graphic user interface, as shown and described.

DESCRIPTION

FIG. 1 is a front view of a portable information terminal having a graphical user interface, showing my new design; FIG. 2 is a rear view thereof;

FIG. 3 is a top plan view thereof;

FIG. 4 is a bottom plan view thereof;

FIG. 5 is a right side view thereof; and,

FIG. 6 is a left side view thereof.

The broken lines in the drawings show portions of the portable information terminal having a graphical user interface that form no part of the claimed design.
